J. DUVALL

STRIPPER WHEEL

Filed April 27, 1922

Inventor:
James Duvaall

T. J. Geisler
by ATTO

UNITED STATES PATENT OFFICE.

JAMES DUVALL, OF CAMAS, WASHINGTON.

STRIPPER WHEEL.

Application filed April 27, 1922. Serial No. 556,874.

To all whom it may concern:

Be it known that I, JAMES DUVALL, a citizen of the United States, and a resident of Camas, county of Clark, and State of Washington, have invented a certain new and useful Improvement in Stripper Wheels, of which the following is a specification.

One of the main objects of my invention is to provide simple and efficient means for expediting the delivery of stock from a rotary cylinder printing press.

A further object is to provide a stripper wheel which is especially adaptable to handle paper bags and other relatively stiff paper. This stripper wheel positions the stock on a conveyor belt without crumpling and also lessens the danger of smearing the fresh ink.

20 A further object is to provide a stripping means for removing the stock from the press shown and described in Patent No. 1,207,149, issued Dec. 5, 1916, to myself, entitled Pneumatic press feeding means.

25 These and other objects are attained in mechanism comprising a toothed wheel or wheels located opposite the rotary cylinder but spaced therefrom, and driven in the opposite direction, the teeth of said wheels being under cut so as to provide a recess at each tooth root and a portion overhanging such recess thereby adapting said overhanging tooth portion to strike the stock and cause it to slip into said recess, in so doing firmly holding the stock and pulling it away from said cylinder and throwing it at a tangent downward therefrom. These objects are shown in the accompanying drawings, in which:

40 Fig. 1 is a diagrammatic representation of a rotary printing press and shows my stripper wheel positioned adjacent the type or plate cylinder;

Fig. 2 is an end elevation of Fig. 1 and 45 shows my stripper wheel positioned opposite the longitudinal middle of said type or plate cylinder;

Fig. 3 is a diagrammatic representation of the train of gears used to drive the 50 stripper wheel; and

Fig. 4 is a diagrammatic representation of the stripper wheel and shows how the teeth pull the paper away from the rotary cylinder.

The construction and operation of my device is as follows:

The press on which I have shown my stripper wheel consists of a frame *a*, a stock holding rack *b*, feeding cylinder *c* and pinch roll *d*. The stock is fed from the rack *b* and pulled downward between the feeding roll *c* and pinch roll *d* and forced between the type or plate roll *e* and the impression roll *f*. The type or plate roll is of course covered with ink and the paper stock will adhere to it if too much ink is applied. Thus, the stripper wheels *g* are designed to prevent the stock *h* from being carried upward with the ink covered roll. The stripper causes the stock *h* to be deflected downward on a tangent from the type or plate roll to the conveyor belt *i* mounted on the pulleys *j* and *k*, mounted on the shafts *j'* and *k'* respectively.

The impression roll *f* is driven by the gear *f'* mounted on a shaft *f''*, the type or plate roll *e* by the gear *e'* mounted on shaft *e''*, and the intermediate gear *l* mounted on the shaft *l'*, meshes with the gear *e'* which also meshes and drives the stripper wheel gear *g'* mounted on the shaft *g''*. The stripper wheel gear being mounted on the opposite side is driven in the opposite direction to the one in which *e'* revolves. The stripper wheels *g* are made with saw like teeth *m* under which the recessed portion *n* is provided. Stock *h* moving directly forward strikes this recess and is deflected downward and away from the type or plate roll. The lip *m'* prevents the stock from passing over the top of the stripper wheel.

I claim:

1. In combination with a printing press having a rotary cylinder, of means for stripping the printed article from the latter consisting of one or more toothed wheels located adjacent said cylinder and driven in the same direction, the teeth of said wheel being of ratchet type inclined in the direction of rotation of the wheel, whereby the end of the article is pulled from said cylinder and thrown at a tangent downward therefrom.

2. In combination with a printing press having a rotary cylinder, of means for stripping the printed article from the latter, consisting of one or more toothed

2
wheels located adjacent and spaced from said cylinder and driven in the same direction, whereby the end of the article is pulled from said cylinder and thrown at a tangent 5 downward therefrom.

3. In combination with a printing press having a rotary cylinder, of means for stripping the printed article from the latter, consisting of one or more toothed 10 wheels located adjacent and spaced from said cylinder and driven in the same direction, the teeth of said wheel being of ratchet type inclined in the direction of rotation of the wheel, whereby the end of 15 the article is pulled from said cylinder and thrown at a tangent downward therefrom.

4. In combination with a printing press having a rotary cylinder, of means for stripping the printed article from the latter, consisting of one or more toothed 20 wheels located adjacent said cylinder and driven in the same direction, the teeth of said wheel being under cut so as to provide a recess at each tooth root, and a portion overhanging such recess, thereby adapting said overhanging tooth-portion to strike the article and cause it to slip into the said recess, in so doing firmly holding the end of the article so seized, pulling it away from said cylinder, and throwing it so at a tangent downward therefrom.

JAMES DUVALL.
